GEORGE C. WINCHESTER, OF ASHBURNHAM, MASSACHUSETTS.

Letters Patent No. 85,883, dated January 12, 1869.

IMPROVED WOOD SEAT FOR CHAIRS.

The Schedule referred to in these Letters Patent and making part of the same.

To all whom it may concern:

Be it known that I, GEORGE C. WINCHESTER, of Ashburnham, in the county of Worcester, and State of Massachusetts, have invented an Improvement in Wooden Chair-Seats; and I do hereby declare that the following, taken in connection with the drawings which accompany and form part of this specification, is a description of my invention sufficient to enable those skilled in the art to practise it.

My invention relates to the construction of wooden chair-seats, with reference to provision for strengthening the same against liability to crack, and with reference to imparting a finished edge to the seat.

In the manufacture of wooden-seated chairs, it is quite common to apply strips beneath the seat, near the edge, such strip or strips running across and lengthwise of the grain. But, besides adding to the thickness of a seat, such construction is objectionable, in that it leaves the end-grain of the seat-wood exposed at the edge of the seat, such end-surfaces being hard to finish in uniformity with the edge-surface of the wood running lengthwise of the grain; and in this respect, wooden seats, each made entirely of a single piece of wood, are open to the same objection.

My invention consists in a wooden chair-seat, the perimeter of which is formed of a reinforcing-strip of wood, bent circumferentially around, and so as to enclose, like a band or hoop, the outer edge of the seat-wood, the upper surface or portion of the seat-wood preferablylapping over the edge-strip, so as to present an unbroken or unseamed top surface to the extreme edge.

The drawings represent a chair-seat embodying my improvement.

A shows a bottom view of the seat.

B, a cross-section of the same.

a denotes the main seat-wood, preferably made in

one piece, with the grain running lengthwise of the chair, from front to rear.

b, the reinforcing and edge-finishing strip.

This strip is made a little deeper than the thickness of the seat a, and, where projecting below the seat, it may have a shoulder or flange, c, upon which the wood a rests, as seen at B; and the top of the seat a has, at its edge, a thin projecting piece, d, which laps over and covers the top of the strip b, as also seen at B.

The strip b is preferably a long piece, formed to have cross-sectionally the flange c, and of length sufficient to encompass the edge of seat a.

This strip being made flexible, and bent to proper form, its two ends are joined together, and it then constitutes a rim, to receive and enclose the edge of seat a, which is pressed into the rim and glued thereto.

It will be seen that the strip adds nothing to the thickness of a chair-seat, as the piece a can be made of thinner stock than when its edge is left unstrength-ened, and that the edge of the seat presents a continuous uniform wooden boundary, in which the fibre of the wood runs lengthwise entirely around the edge, while the upper surface is also unseamed, or is free from any joint.

Chair-seats thus made are very strong, durable, and inexpensive, and are adapted to changes of climate as well as to rough usage.

I claim a wooden chair-seat, having an encompassing band or strip b, made in one piece, and running around the seat-wood a, and forming the edge thereto, substantially as shown and described.

GEORGE C. WINCHESTER.
